UNITED STATES PATENT OFFICE.

THOMAS B. TIEFENBACHER, OF NEW YORK, N. Y.

TOOL-HOLDER FOR LATHES.

SPECIFICATION forming part of Letters Patent No. 721,979, dated March 3, 1903.

Application filed October 1, 1902. Serial No. 125,483. (No model.)

To all whom it may concern:

Be it known that I, THOMAS B. TIEFENBACHER, a citizen of the United States, residing in New York, borough of Manhattan, 5 and State of New York, have invented certain new and useful Improvements in Tool-Holders for Lathes, of which the following is a specification.

This invention relates to an improved tool-holder for lathes which is supported in the slide-rest in such a manner as to be capable of close and accurate adjustment to the work, so that not only a better support for the tool, but also a greater range of adjustment of the 15 same relatively to the work is obtained; and for this purpose the invention consists of a tool-holder for lathes which comprises an upright post supported by a base-plate, a clamping-plate placed on the base-plate, a second 20 clamping-plate placed on the post, clamping-jaws on said clamping-plates, means for adjusting the latter to the tool clamped between them, means for adjusting the upper clamping-plate on the post, and an auxiliary 25 set-screw connecting the rear end of the upper clamping-plate for setting the latter to the size of the tool to be clamped between the jaws; and the invention consists, further, of 30 certain details of construction and combinations of parts, which will be fully described hereinafter and finally pointed out in the claims.

In the accompanying drawings, Figure 1 represents a side elevation of an engine-lathe with my improved tool-holder supported on the slide-rest of the same. Fig. 2 is a side elevation of the slide-rest and tool-holder, drawn on a larger scale. Fig. 3 is an end elevation of the tool-holder, drawn on a 40 still larger scale. Fig. 4 is a plan view of Fig. 3. Fig. 5 is a vertical transverse section on line 5 5, Fig. 3; and Fig. 6 is a detail vertical transverse section of the upper portion of the supporting-post and of the screw-nut for tightening up the clamping-plate of 45 the tool-holder.

Similar letters of reference indicate corresponding parts.

Referring to the drawings, A represents the 50 slide-rest of an engine-lathe. The lower part a of the slide-rest is actuated in the usual manner by a screw-spindle G and hand-wheel

B, while the upper part a' is transversely guided on the lower part a by means of dove-tailed guideways t and a screw-spindle B', so 55 as to adjust the upper part of the slide-rest and the tool supported thereon to the proper relative position toward the work supported by the centers of the lathe.

My improved tool-holder is supported on 60 the upper part a' of the slide-rest A by means of an upright post D, which is provided with a base-plate d, that is supported in a corresponding undercut recess of the upper portion a' of the slide-rest, as shown in Fig. 3. 65 On the upper portion a' of the slide-rest is supported a lower clamping-plate E, which is provided with an opening and is placed on the post D, while a second clamping-plate E', provided with an opening corresponding to 70 the diameter of the post D, is also placed on the post D above the lower clamping-plate E. A helical spring h is interposed between the two clamping-plates. The faces of the clamping-plates E E' are provided with concave recesses for supporting the convexly-curved sides of segmental jaws F F', the faces of the jaws being serrated for gripping the tool to be held between them. The lower clamping-plate E is connected by a guide-pin 75 f with a recess f' in the lower jaw F, so as to be guided thereby on the clamping-plate into inclined position. The jaw F' is similarly adjusted and clamped to the clamping-plate E' by a clamping-screw f², which passes 80 through an arc-shaped slot f³ in the clamping-plate, as shown clearly in Figs. 3 and 5. The clamping-block E, as well as the clamping-plate E', are provided with projections g g', against which the tool abuts when it is 85 placed between the serrated faces of the jaws, so as to be prevented from being moved farther back than the projections. The upper end of the upright post D is screw-threaded, so that a screw-nut D' can be screwed down 90 on the same, said screw-nut being provided with a convexly-curved lower part or base D², that rests on a washer d² and presses the latter on the upper face of the clamping-plate E', said washer being provided with a concaved upper face adjacent to the convex lower part or face D² of the screw-nut D', as 95 shown clearly in Fig. 6.

The clamping-plate E' is made of approxi-

mately V or triangular shape and provided in the end opposite to its tool-holding end with an interiorly-threaded hole e^2 , which is engaged by an auxiliary screw E^2 , the lower 5 end of which is extended into a recess e^3 of the lower clamping-plate E, said recess being vertically below the hole e^2 and extended laterally for the purpose of giving sufficient play to the auxiliary screw E^2 and also for 10 keeping the recess clear of dust, chips, &c. The lower part of the auxiliary screw E^2 is provided with a hexagonal shoulder, so as to permit the return of the auxiliary screw E^2 and the tight application of the upper clamping 15 plate or jaw by means of a wrench.

When a tool is to be placed between the jaws of the upper and lower clamping-plates, the jaws adjust themselves to the proper inclination of the tool, as required by the work.

20 The upper jaw is then clamped in its proper position and the screw-nut D' screwed down on the post, so as to clamp the tool firmly between the jaws F F'. Between the clamping-plates E E' is interposed on the post D a 25 helical spring h, which serves to support the upper clamping-plate, so as to raise it again as soon as the screw-nut is turned in opposite direction on the threaded end of the post D. While the jaws are clamped to the tool, the 30 auxiliary screw E^2 is in raised position in the upper clamping-plate E'. The serrated faces of the clamping-jaws impart a firm hold on the shank of the tool, while the convex face of the lower portion or base of the screw-nut 35 D' and the concave face of the washer permit the ready adjustment of the upper jaw to any slight inaccuracies or unevenness in the tool-shank, so that the jaws cannot lose their grip on the same. When the tool is thus placed 40 in proper position, the auxiliary screw E^2 is turned down until it abuts against the lower clamping-plate, and the screw-nut D screwed down by the wrench, so as to impart the final clamping action to the tool and set thereby 45 the tool-holder firmly and reliably to the work.

My improved tool-holder has the advantage of permitting the quick and convenient adjustment of the tool close to the work with little strain on the slide-rest and of holding the 50 tool firmly and reliably in position at any required angle of inclination required by the work to be done.

Having thus described my invention, I claim as new and desire to secure by Letters 55 Patent—

1. In a tool-holder for engine-lathes, the combination with the slide-rest, of an upright post supported in the slide-rest, a lower clamping-plate supported on the slide-rest 60 and post, an upper clamping-plate also supported on the post, means for adjusting the upper clamping-plate on the post, segmental jaws supported by the clamping-plates, means for adjusting the segmental jaws, projecting

70 lugs on the clamping-plates between the post 65 and segmental jaws for holding the tool in place, and an auxiliary screw engaging the ends of the upper and lower clamping-plates opposite the jaw-carrying ends, substantially as set forth.

2. In a tool-holder for engine-lathes, the combination, with an upright post supported in the slide-rest and provided with a threaded upper end, of a lower clamping-plate supported on said post and slide-rest and provided with a lateral recess, an upper clamping-plate also supported on the post, segmental jaws supported by the clamping-plates, means for adjusting said jaws in the recessed faces of the clamping-plates, a 80 screw-nut on said post, a washer interposed between the upper clamping-plate and screw-nut, and an auxiliary screw between the ends of the upper and lower clamping-plates opposite to the jaw-carrying ends and located 85 in the recess of the lower clamping-plate, substantially as set forth.

3. In a tool-holder for engine-lathes, the combination, with an upright post supported in the slide-rest and provided with a threaded 90 upper end, of a lower clamping-plate supported on the slide-rest and the post, an upper clamping-plate supported on said post, a screw-nut on the upper threaded end of said post, said screw-nut being provided with a 95 convexly-curved base, a washer interposed between the upper clamping-plate and the base of the screw-nut, said washer being provided with a concave face adjacent to said base, and an auxiliary screw connecting the 100 ends of the clamping-plates opposite the jaw-carrying ends, substantially as set forth.

4. In a tool-holder for engine-lathes, the combination with an upright post supported in the slide-rest, of a lower clamping-plate 105 supported on the post and slide-rest and provided with a segmental recess and a projection adjacent to said recess, an upper clamping-plate placed on the post and also provided with a segmental recess and projection adjacent to said recess, a helical spring interposed between the upper and lower clamping-plates, segmental jaws arranged in the recesses of the clamping plates, means for adjusting said jaws, a screw-nut on the upper threaded end 115 of the post, a washer between said screw-nut and the upper clamping-plate, and an auxiliary screw connecting the ends of the clamping-plates opposite to the jaw-carrying ends, substantially as set forth.

120 In testimony that I claim the foregoing as my invention I have signed my name in presence of two subscribing witnesses.

THOMAS B. TIEFENBACHER.
